To all whom it may concern:

Be it known that I, LEVI H. Figure 1 is a side view of a bottle as designed by me. Fig. 2 is a sectional view through the center of the same, and Fig 3 is a top view.

As will be seen from the drawings, my design contemplates a round bottle.

The features of the design are the bowl A, with the curves B and C at the top and bottom, having a straight space or panel D between the beads E E, together with the neck F, having a rim or lip G at its mouth. 20

What I claim is—
